UNITED STATES PATENT OFFICE.

HARRY H. WIGGLESWORTH, OF PHILADELPHIA, PENNSYLVANIA, ASSIGNOR TO THE PHILADELPHIA DRYING MACHINERY COMPANY, OF PHILADELPHIA, PENNSYLVANIA, A CORPORATION OF PENNSYLVANIA.

DRIER FOR HOSIERY.

Application filed May 13, 1924. Serial No. 712,966.

This invention relates to machines for drying hosiery and other knitted articles, and it has for a primary object the provision of a machine including a continuous guideway over which detached form carriers are traversed in intimate proximity while in the drying enclosure, but spaced apart when exterior thereto for clothing and stripping.

Another object is to provide a machine of the above typified form characterized by automatically actuated ingress and egress closure instrumentalities, whereby increased efficiency and economy are attained.

Other objects and attendant advantages inhering to this invention will be later on referred to or particularized, and said invention may be tersely expressed as consisting in the novel features of construction, combinations and arrangements of parts hereinafter fully described, and thereafter succinctly defined by the appended claims.

In the further disclosure of the invention reference is to be had to the accompanying sheets of explanatory drawings, constituting a part of this specification, and in which corresponding parts are distinguished by the same indices throughout the several views.

Fig. I, is a front elevation of a hosiery drying machine conventionally embodying this invention.

Fig. II, is a plan view with a portion broken away to better disclose certain interior features.

Fig. III, is a vertical sectional view on the line III—III in the preceding illustration.

Fig. IV, is a fragmentary detail view of one of the automatic closures hereinafter fully explained.

Fig. V, is a view looking towards the right hand of the preceding figure.

Fig. VI, is a fragmentary detail view illustrating the drying enclosure construction.

Fig. VII, is a side elevation of the complete drying machine with a fragment of the enclosing wall removed to disclose certain interior parts.

Fig. VIII, is an enlarged rear elevation of a shifter mechanism for the forms when exterior to the drying enclosure; and

Fig. IX, is a detail plan view of the form carrier progressing mechanism.

According to the embodiment of my in-

vention illustrated I construct a rectangular framework of standard section verticals 10, braced by similar section horizontals 11, and closed in by thermo-insulated plates to provide an enclosure 12 in spaced relation to the floor level 13. This enclosure 12 is provided with a roof 14 having an inverted frusto-pyramidal portion or deflector 15, for a purpose hereafter explained; and a bottom 16 having a guideway therein constituted by parallel slots 17, 17' connected by a rear arcuate course 18; and said parallel slots communicate, at the front of the machine, with vertical openings 19, 20,—Fig. I—in the enclosure wall 21, respectively affording ingress and egress for the forms 22, as latter are fully set forth.

Conveniently mounted within the enclosure 12, and supported by standard section verticals 23, in spaced relation to the bottom 16, is a rectangular conduit 24 conventionally housing a plurality of radiators 25, through which heating medium is circulated in accordance with prevailing practice. Appropriately secured to opposed verticals 23 in the upper part of the conduit 24 is a housing 26 for the horizontally rotatable fan 27; the shaft 28 whereof is journaled in a bearing 29, supported concentrically within the frusto-pyramidal deflector 15, aforesaid. Rotary motion is imparted to the fan 27 through the medium of a miter couple 30, driven by a horizontal countershaft 31, journaled in bearings 32, secured on the roof 14 of the enclosure 12; and said countershaft is conveniently rotated by a belt transmission 33 from any convenient source of power. Incidentally, it is noteworthy that the disposition of the conduit 24 within, and relatively spaced with respect to the interior of, the enclosure 12 provides a corridor or passageway 34, in which the actual drying operation is effected; while the arrangement of the fan housing 26 concentrically below the frusto-pyramidal deflector 15 ensures effective diffusion of the drying medium with a looped directional flow as clearly indicated by the arrows on Fig. III.

Referring to the forms 22, each of which is removably supported by an individual carrier shoe 35 of sexangled configuration in plan with upstanding flanges 36, between which the said forms are securely clamped,

in any of the well known ways. Furthermore, the upstanding flanges 36 are fitted with opposed angle sections 37, the lateral portions whereof are adapted to snugly fit transversely across the slots 17, 17' aforesaid, whereby the latter are closed-in against wasteful escape of the heating medium, as will be appreciated by an examination of Figs. II and III, more particularly. Still further it is to be noted that each carrier shoe 35 is provided centrally at its underside with a pin or stud 38 afforded guidance in a trackway 39, comprising oppositely directed co-planar angle sections sustained by similar section posts 40 rigidly braced to the machine sub-structure in any convenient manner. This trackway 39, as best understood from Figs. II and VII is configured to provide parallel side or "entrance" and "exit" portions 41, 41', extending rearwards from the front of the enclosure 12, in parallel relation below the bottom 16, with a connecting arcuate back end 42; and said trackway is disposed co-planar with a platform 43, having a rectangular slot 44 therein, and an upstanding frontal flange 45 affording guidance for the carrier shoes 35 during progression exterior of the enclosure 12. It is, however, to be remarked that the rectangular slot 44 is co-extensive with, and constitutes a part of the course traversed by the carrier shoe pins or studs 38. In connection with the platform 43, there is fitted a rectangularly configured sheet metal embossment 46, the shorter ends whereof align with the inner vertical flanges of the trackway 39, as clearly shown in Fig. II.

Having set forth the structural characteristics of the drying enclosure 12 and the detached form carrier shoes 35, I will now describe the mechanism effective to progress the series of forms 22 through the corridor 34, in abutting relation, as well as traversing the same relatively spaced apart while outside the enclosure 12, for stripping and clothing. The said mechanism is operated through the medium of a coned pulley 47 on the countershaft 31, and belt transmission 48, adapted to drive a reversely stepped pulley 49 secured on a short shaft 50, journaled in bearings 51 mounted in the machine sub-framework. Secured on, or integral with, the shaft 51 is a worm 52 in gear with a worm wheel 53, splined to a horizontal shaft 54 journaled in bearings 55, mounted on angle section cross-braces 56 in the machine sub-structure. This horizontal shaft 54 is fitted at its front end with a crank arm 57, in turn connected by a pitman 58 to a vertically movable lever arm 59, fulcrumed at its lower end to a pivot block 60, rigidly supported by the machine framework. Pivotally connected to the upper end of the lever arm 59, is a link 61, in turn similarly cou-

pled to a slide bar or shifter 62, adapted for longitudinal reciprocation relative to a suitable guide 63, as later on fully described. The guide 63 is conveniently a standard angle-section rigidly secured across the front 70 of the machine framework in juxtaposed relation below the platform 43, with its vertical limb slotted at 64 to receive lateral studs 65, 66 on the shifter 62, the former of which also serves as a pivot for the upper end 75 of the link 61, as best shown by Fig. I. Pivoted by studs 67 to the rear face of the shifter 62, are a pair of pawling members 68, provided with lateral arcuately-curved teeth 69, adapted to cooperate with the carrier shoe pins or studs 38, to effect exterior progression of successive forms 22, in the manner hereafter set forth; and said pawling members 68 are prevented from oscillation, otherwise than as later on explained, 80 by stops 70, provided for the purpose on the back face of the shifter 62.

Simultaneously co-operative with the means just explained is a triple-acting pusher mechanism now to be described. This mechanism includes a double-ended horizontally movable lever arm 71, fulcrumed by a stub-shaft 72 in bearings 73, 74 the former 73 of which is rigidly secured to the underside of the embossment 46 hereinbefore referred to, whereas the latter 74 is firmly attached to one of the verticals 10; and a second relatively longer lever arm 75 similarly pivoted by an appropriate bearing 76 fixed to the bottom 16 of the enclosure 12. These lever arms 71, 75 are co-ordinated by a multiplying linkage 77, 78 so that the throw of the latter lever arm, 75, is relatively greater than that of the former, 71, for a purpose later on explained; and each lever is fitted 100 at its outer end with a spring influenced finger 79. Oscillation of the triple-acting pusher mechanism is effected by means of a forked tappet member 80, attached on the stub shaft 72, being disposed in the path 105 of movement of a vertical pin or projection, 81, on the end of the pitman 58, where it is pivoted at 82 to the vertically movable lever arm 59, as best shown in Figs. I and IX.

Associated with, and simultaneously actuated by, the triple-acting pusher mechanism 71, 75 is a means for automatically opening and closing sliding doors 83, 84 to permit ingress and egress of the forms 22, through the openings 19, 20 relative to the drying corridor 34. These doors 83, 84, as best shown in Figs. I, IV and V, are suspended in the well known way by antifriction rollers 85 adapted to traverse the hanger track 86, each said door being operated by means of a quick-action compound or translating leverage 87, 88; the latter member 88 being fulcrumed at 89 to the machine framework, and provided with a crank arm 90. Appropriately attached to

the free end of the crank arm 90 is a universal connection 91, in turn hinged to a rock member 92, fulcrumed at 93 to the platform 43, and having a downwardly inclined cam face 94 with which the aforesaid double-ended lever arm 71 operatively engages, and is adapted to swing the rock member 92 upwardly to effect opening of the doors 83, 84. These doors 83, 84 are adapted to gravitate back to closed position in the well known way.

Having detailed the several coordinated mechanisms incorporated in my novel automatic drying machine for hosiery and other knitted articles, the operation thereof may be briefly summarized as follows:

Assuming the machine is designed for drying hosiery and that clockwise motion is imparted thereto by the belt drive 33, it will be obvious that the crank arm 57 will be constantly rotated by the worm drive 52, 53 in a counter-clockwise direction thereby swinging the lever arm 59 with a to-and-fro motion in a vertical plane, and intermittently reciprocating the slide bar or shifter 62 from the right to the left-hand with respect to Fig. I, and vice versa. Now it will be readily apparent from the preceding descriptive matter, relating thereto, that reciprocation of the slide bar or shifter 62 will effect horizontal oscillation of the triple-acting lever arms 71, 75. Now, let it be assumed that said lever arms 71, 75 occupy the respective positions shown in Figs. II and IX, rocking of the lever arm 59 to the left-hand will advance the pin 81 into engagement with the bifurcated tappet member 80 and partially turn the stub shaft 72 about its axis, whereby the double-ended lever arm 71 will withdraw a form carrier 35 from the corridor 34 to the position designated *a*—Fig. II—in the platform rectangular slet, whereat the "stripper" operative is stationed to remove the dried article. Concurrently therewith, the form carrier 35 at the position designated *b*, whereat the "boarder" operative is stationed to reclothe successive forms 22 with wet articles, will be advanced into the drying corridor 34, and simultaneously stripped form carriers located at *c* and *a*, will be progressed by the pawling members 68 to the positions denoted as *b* and *c* respectively. Now it will be perfectly obvious that the sliding doors 83, 84 will have been automatically opened to permit the egress and ingress form carrier progressions just described, and it is pointed out purely by way of clarifying such operations that if the dwell period of time intervening each progressive movement of successive form carriers 35 be assumed as fifteen seconds, the door actuating mechanism can be designed so that the doors 83, 84 only remain open for three seconds so that escape of the drying medium from the

corridor 34 is purely negligible. Furthermore, it will be clearly seen that simultaneously with the co-ordinated operations just explained a form carrier 35 will have been progressed over the arcuate end 42 of the trackway 39, from the "entrance" side 41, to the "exit" side 41', by means of the lever arm 75. Obviously movement of the slide bar or shifter 62 on the return stroke or towards the right hand in Figs. I and II will result in a reverse motion being imparted to the lever arms 71, 75, which, by virtue of their spring influenced finger ends 79, will release the respective form carriers 35 advanced as above described, and said arms will be returned to re-operative position as will be readily understood by anyone in the least acquainted with the art. Particular attention, however, is directed to the fact that the several form carriers 35 are progressed along the "entrance" and "exit" sides 41, 41' of the trackway 39 in intimate contact, whereas they are advanced over the platform 43 relatively spaced apart.

From the foregoing description it is thought that the progressive course of the form carriers 35, will be fully understood without further explanation, while the attendant economic advantages inhering to my novel drying machine are so apparent as not to necessitate specific tabulation. Finally, the assemblage illustrated and explained in detail, is not to be conservatively construed, as numerous changes and modifications in the general aggroupment of parts will naturally suggest themselves in accommodating the machine for drying different articles; therefore, the right is reserved to make all such reasonable variations that fairly lie within the scope of the subjoined claims.

Having thus described my invention, I claim:

1. A machine for drying hosiery and the like including a drying enclosure, a continuous trackway associated with said drying enclosure, a series of detached form carriers traversable over the trackway, and co-ordinated pawling means functional to progress the form carriers in intimate contact with an intermediate transfer period relative to the drying enclosure but spaced apart when exterior thereto.

2. A machine for drying hosiery and the like including a drying corridor, a continuous polygonal trackway below and partly exterior of said drying corridor, a series of detached form carriers traversable over the trackway, and co-ordinated lever devices functional to intermittently progress the form carriers in intimate contact—with an intermediate transfer stage—relative to the drying corridor but spaced apart when exterior thereto.

3. A machine for drying hosiery and the

like including a rectangular corridor, a continuous trackway including an arcuate portion aligned below and partly exterior to said corridor, a series of detached polygonally configured form carriers traversable over the trackway, and pawling devices functional to progress said form carriers in intimate contact—with individual transfer over the arcuate portion—relative to the drying corridor but spaced apart while exterior thereto.

4. A machine for drying hosiery and the like including a rectangular drying corridor, a continuous trackway having parallel portions with a connecting arcuate portion aligned below the drying corridor and a rectangular portion exterior thereto, a series of detached form carriers traversable over the trackway, and pawling levers functional to progress the form carriers in intimate contact over the parallel portions of the trackway but in separated relation over the arcuate and rectangular portions aforesaid.

5. In a drying machine of the type described a series of detached form carriers, means operative to intermittently progress the detached form carriers comprising triple-acting lever arms with a multiplying connection, and coordinated reciprocatory means adapted to advance said form carriers while not subject to progression by the triple-acting lever arms aforesaid.

6. In a drying machine of the type described, a series of detached form carriers, means operative to intermittently progress the detached form carriers comprising triple-acting lever arms with spring controlled finger ends and a multiplying connection, and coordinated reciprocatory means adapted to spacedly progress said form carriers when not subject to movement by the triple-acting lever arms aforesaid.

7. In a drying machine of the type described, a series of detached form carriers, means operative to intermittently progress the detached form carriers comprising a double-ended lever arm and a single-ended lever arm with a multiplying connection between the former and latter, and coordinated reciprocatory means adapted to advance the

form carriers when not subject to progression by the lever arms aforesaid.

8. In a drying machine of the type described, a series of detached form carriers, means operative to intermittently progress the detached form carriers comprising a double-ended lever arm and a single-ended lever arm with a multiplying connection between the former and the latter, and reciprocatory pawling means adapted to spacedly advance successive form carriers when not subject to progression by the lever arms aforesaid.

9. In a drying machine of the type described, a series of detached form carriers, means operative to intermittently progress the detached form carriers comprising a double-ended lever arm and single-ended lever arm with a multiplying connection therebetween, reciprocatory pawling means adapted to spacedly advance successive form carriers when not subject to progression by the lever arms aforesaid, and co-ordinated motion translating mechanism functional to swing the aforesaid lever arms with simultaneous reciprocation of the pawling means.

10. A drying machine of the character described including a drying corridor having ingress and egress apertures, means adapted to progress a series of form carriers therethrough, closures for said apertures, and means actuated by the form progressing means to retract said closures simultaneously with withdrawal and entry of successive form carriers relative to the drying corridor.

11. A drying machine of the character described including a drying corridor having ingress and egress apertures and means adapted to progress a series of form carriers therethrough, closures for said apertures, and quick-action compound levers operable by the form progressive means to retract the closures simultaneously with withdrawal and entry of consecutive form carriers relative to the drying corridor.

In testimony whereof, I have hereunto signed my name at Philadelphia, Pennsylvania, this 10th day of May, 1924.

HARRY H. WIGGLESWORTH.
